UNITED STATES PATENT OFFICE.

THOMAS SPENCER, OF ATLANTA, GEORGIA.

PLOW.

SPECIFICATION forming part of Letters Patent No. 269,734, dated December 26, 1882.

Application filed October 16, 1882. (Model.)

To all whom it may concern:

Be it known that I, THOMAS SPENCER, a citizen of the United States, residing at Atlanta, in the county of Fulton and State of Georgia, have invented certain new and useful Improvements in Plows; and I do hereby declare that the following is a full, clear, and exact description of the same, reference being had to the annexed drawings, making a part of this specification, and to the letters and figures of reference marked thereon.

Figure 1 of the drawings is a perspective view, and Fig. 2 a longitudinal vertical section, of my invention.

This invention relates to certain new and useful improvements in plows for breaking and working rough ground; and the object of the present invention is to produce a plow that will yield or relieve itself from any obstructions—such as stones, roots, or stumps—that may come in contact with the points in the line of draft, without lifting of the plow by the operator, or strain upon the team, thus decreasing and lightening the labor of both. A further object is to provide a means whereby the plow may be readily drawn from one place to another without turning it upon the side, thereby lessening the drag, while at the same time the said plow or plows may be relieved of all dirt, brush, or other trash that may have accumulated thereon. These objects I attain by the construction substantially as shown in the accompanying drawings, and hereinafter described.

In the drawings, A represents a rectangular frame having handles B and beam C, said beam being suitably braced by rods or plates a, extending from bearings b, midway upon the under faces of the side pieces of the frame to the forward end of said beam. In these bearings b revolves a suitable shaft, D, to which is adjustably keyed an arm-case, E, carrying a series of plow-points or harrow-teeth, F, adjustably connected thereto, said arm-case making a partial or entire revolution with the shaft, as occasion may require, and hereinafter described.

At one end of the shaft D is fitted a ratchet or cam wheel, c, having indentations or projections equal in number to the plows or teeth attached to the arm-case E, into or on which a catch, d, engages itself to hold the plow in

proper position until the same comes in contact with some obstacle too great for the power applied to overcome. This catch d is connected by means of a rod, e, to a pivoted bar or plate, f, which in turn connects by a rod, g, with the clevis h, which works by suitable connections in a slot, i, in the end of the beam C to raise said catch from the ratchet or cam wheel c when the plow-point comes in contact with an unyielding obstruction, allowing said plow-point to turn back and give place to the next, the catch d engaging with the next indentation or projection upon the wheel c as the shaft D, carrying the arm-case E, makes a partial revolution. The catch d is raised to disengage itself with the ratchet or cam wheel c by the bolt m pressing in an outward direction against the end of the rod g, or that portion of the rod or its connection extending laterally through the slot i in the beam C as the clevis is drawn forward.

The degree of force required before the plow will yield to an obstruction is regulated by means of a spring, G, or its equivalent, attached to the beam C and regulated by a screw or bolt, h, passing through the bar or plate f, and bearing on said spring to give it the required tension.

When the plow strikes an obstruction—say a root, for instance—and falls back the next plow does not come into action until sufficient ground has been passed to clear said obstruction, and thus little or no check is given to the team or operator, thereby allowing the breaking or working of rough ground without sudden stops or jerks, which are annoying to the operator and irritating to the team, and often break or otherwise damage the plow.

Should the plow become clogged, or the operator for any other reason desire to relieve it, he forces down a lever, H, pivoted to one of the side pieces of the frame, with its end shaped so as to come under the catch d, thereby raising said catch and admitting of the plow's revolving, thus doing away with the necessity of turning the plow upon its side, as is usually done with plows of the ordinary construction.

A stirrup or trigger, I, is pivoted at its extreme lower end to the rear cross-piece of the frame A, and extends out laterally toward one of the handles B, and up through a guidesleeve or band, l, encircling the handle. The extreme

upper end of the stirrup or trigger I is bent, as shown at *n*, to extend over the lever H. Now, when it is desired to hold the catch *d* disengaged with the wheel *e* the lever H, when 5 pressed down, will raise the catch, as hereinbefore stated, and by pressing up the stirrup or trigger I the curved or bent end *n* will be brought over the lever and hold it pressed against the catch, thus allowing the shaft D to 10 freely turn within its bearing. When desired to again bring the plow into action this stirrup or trigger is pushed down by the foot of the operator. By this action the lever is released and the catch engages with the ratchet 15 or cam wheel upon the shaft carrying the arm-case.

Although I have described my invention as particularly applicable to plows for breaking and working rough ground, the same may be 20 used for harrowing, and a double set of plows or teeth may be employed upon the shaft, if desired.

Having now fully described my invention,

what I claim as new, and desire to secure by Letters Patent, is—

25

1. The rod *g*, connected to the clevis *h*, in combination with the spring *G*, bar or plate *f*, and set-screw *k*, substantially as and for the purpose described.

2. The combination, with the ratchet-wheel 30 *e* and pivoted catch *d*, of the lever H and stirrup or trigger I, substantially as and for the purpose set forth.

3. The spring *G* and pivoted bar or plate *f*, and the rods *eg*, in combination with the clevis 35 *h*, bolt *m*, shaft D, carrying plow-points or harrow-teeth, the wheel *e*, and catch *d*, substantially as and for the purpose specified.

In testimony that I claim the above I have hereunto subscribed my name in the presence 40 of two witnesses.

THOMAS SPENCER.
